US00D853844S

(12) **United States Design Patent** (10) **Patent No.:** **US D853,844 S**
(45) **Date of Patent:** **** Jul. 16, 2019**

(54) **STORAGE TRAY FOR HOROLOGICAL GOODS**

(71) Applicant: **NIVAROX-FAR S.A.**, Le Locle (CH)

(72) Inventor: **Roger Juillet**, Fontanemelon (CH)

(73) Assignee: **Nivarox-Far S.A.**, Le Locle (CH)

(**) Term: **15 Years**

(21) Appl. No.: **29/617,936**

(22) Filed: **Sep. 18, 2017**

(30) **Foreign Application Priority Data**

Mar. 16, 2017 (WO) DM/095 810

(57) **CLAIM**

The ornamental design for a storage tray for horological goods, as shown.

DESCRIPTION

FIG. 1 is a left front bottom perspective view of a storage tray for horological goods showing my new design;

FIG. 2 is a right rear top perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

1 Claim, 6 Drawing Sheets
